DESIGN FOR A MILK TESTING DEVICE

Chester A. Thomas, Crystal Lake, Ill.

Application July 8, 1944, Serial No. 114,342

Term of patent 14 years

(Cl. D23—1)

To all whom it may concern:

Be it known that I, Chester A. Thomas, a citizen of the United States, residing at Crystal Lake, in the county of McHenry and State of Illinois, have invented a new, original, and ornamental Design for a Milk Testing Device, of which the following is a specification, reference being had to the accompanying drawing, forming part thereof.

Figure 1 is a side elevational view of a milk testing device showing my new design;

Figure 2 is a plan view of the device shown in Figure 1;

Figure 3 is a bottom view of said device; and

Figure 4 is a side elevational view of the design shown in Figures 1-3 with the two parts thereof separated.

I claim:

The ornamental design for a milk testing device, as shown.

CHESTER A. THOMAS.
